UNITED STATES PATENT OFFICE

JOSEPH A. LEDOUX, OF WORCESTER, MASSACHUSETTS

TRAFFIC MARKER

Application filed June 26, 1930. Serial No. 464,046.

This invention relates to a device for marking highways for traffic purposes and the like.

The principal objects of the invention are to provide a marker which will have a soft and yielding body and surface so that the wear will be comparatively slight; to provide a construction which can be embedded in the pavement permanently as a body but which will have a portion showing the mark removable mounted in such a way that it can be taken out very easily and to provide a construction which will have the same appearance after wear so as to save the recoating of the pavement with paint or other material and thus decrease materially the cost of the markings.

Other objects and advantages of the invention will appear hereinafter.

Reference is to be had to the accompanying drawings, in which

Fig. 1 is a plan of a portion of a pavement with a preferred embodiment of this invention applied thereto;

Fig. 2 is a longitudinal sectional view on the line 2—2 of Fig. 1;

Fig. 3 is a perspective view of the outer part of the device partly broken away;

Fig. 4 is a perspective view of the latch or locking device, and

Fig. 5 is a sectional view on the line 5—5 of Fig. 1.

In order to properly anchor the marker in position, it is made in the form of a casing or box 10 having flanges 11 all around it, or a single flange projecting out from it, at the bottom. This is embedded in concrete or other material of the roadway. Therefore it is permanently mounted in position with its open top flush with the roadway.

This casing 10 is provided with a flange 12 at each end extending inwardly horizontally at its open upper side. The flange is provided with a passage 13 at the center which is flush with the end wall of the casing. The flange 12 is horizontal on the bottom to prevent the device inside from being raised. It is also provided with a slanting surface 14 for a purpose to be described. This constitutes the entire casing.

Inside this casing is located a block 15 of

soft and yielding rubber and if desired, it may have an arrow 16 or any other thing to indicate the direction or any other instructions to be given the driver approaching it or information of any kind. This arrow in the present case is shown as raised above the surface of the block 15 and is formed of a piece of soft rubber of a different color from the body of the block 15. This is one of the ways in which it can be made, but it can also be made flush on the top and of rectangular shape if desired. In each end of this block 15 is a longitudinal opening 17.

On the ends of the rubber block are a pair of latches 20. Each is provided with a horizontal projection 21 extending into the opening 17 to keep it in place. Each latch is also provided with a transverse flange 22 on the end having a horizontal bottom and a central portion extending vertically to a point near the top and has two slanting surfaces 23 at the opposite ends thereof, leaving the center of this portion to extend to the top in a vertical plane. This flange 22 is provided at its end with inclined surfaces 24.

In the insertion of the block in the casing, it being understood that the block is substantially as long as the casing, the two latches are put into the ends of the block as shown in Fig. 2 and then they are forced toward each other, the soft rubber of which the marker is made yielding for that purpose. Then this central portion of the flange 22 in each case passes down through the central opening 13 and allows the block to go down without compressing it. Then the surfaces 24 come right over the surfaces 13 and the rubber block is compressed longitudinally by being forced down. After they have passed down below the flat bottom of the flange 12, the latches will spring back, owing to the resiliency of the rubber, and be held underneath these flanges so there is no danger of these latches coming out accidentally and therefore no danger of the block being displaced.

The two inclined surfaces 23 are employed so that, if it is desired to remove the block, a tool may be introduced along these inclined surfaces to force the latches inwardly

far enough to pass beyond the lower surfaces of the flanges 12, thus freeing the block therefrom and allowing the latches to be taken out with the block.

5 It will be seen that this device does not have to be painted from time to time and a great deal of expense is saved for that reason. At the same time the casing is permanently mounted in the roadway and yet the 10 marker is capable of being removed when desired. It is an inexpensive construction and the holding of the latches in position depends upon the resiliency of the rubber block. Of course, the idea can be used to show directions, stops, crosswalks and center lines and in fact takes the place of all markers placed in the surface of the highway.

Although I have illustrated and described only one form of the invention I am aware 20 of the fact that modifications can be made therein by any person skilled in the art without departing from the scope of the invention as expressed in the claims. Therefore I do not wish to be limited in this respect but 25 what I do claim is:—

1. A traffic marker comprising a cast metal casing having flanges projecting from the bottom embedded in the roadway, said flanges serving to positively unite it therewith, a rubber block located in said casing and projecting slightly above it and having its top surface in the form of the marker desired and a pair of latches at the opposite ends of the rubber block engaging the inner surface of 35 the casing to hold the block in position, the resiliency of the block acting on the two latches to force them against the ends of the casing.

2. A traffic marker comprising an open 40 topped casing embedded in the roadway having a flange extending inwardly at its end, a resilient rubber block in said casing and having its upper surface projecting to the surface of the roadway and constituting the marker proper and a latch set into an opening in the end of the rubber block and adapted to be forced outwardly by the resiliency of the rubber to a point just underneath the said flange to hold the rubber block 45 in position.

3. A traffic marker comprising a casing 50 embedded in the roadway and open at the top, said casing having flanges extending inwardly at its ends, a resilient rubber block in said casing and a pair of latches each set into an opening in the end of the rubber block, said latches and flanges having cooperating slanting surfaces, whereby the forcing of the block and latches downwardly will gradually force the latches nearer together and finally allow them to spring apart so that the surfaces on the latches will rest under the flanges.

4. A traffic marker comprising a casing 55 embedded in the roadway and open at the

top, said casing having flanges extending inwardly at its ends, a resilient rubber block in said casing and having its upper surface constituting the marker proper and a pair of latches each set into a horizontal opening 70 in the end of the rubber block and adapted to be forced out by the resiliency of the rubber to a point underneath the said flanges to hold the rubber block in position, said latches having an inclined surface, whereby when 75 the block is in position the tool can be introduced behind an inclined surface to force the latch back and release it from the flange under which it is normally located.

In testimony whereof I have hereunto af- 80 fixed my signature.

JOSEPH A. LEDOUX.
